METHOD OF TREATING HYDROCARBON OILS

Filed April 24, 1933

UNITED STATES PATENT OFFICE

2,091,624

METHOD OF TREATING HYDROCARBON OILS

John C. Black, Beverly Hills, and Marvin L. Chappell, Watson, Calif., assignors to Union Oil Company of California, Los Angeles, Calif., a corporation of California

Application April 24, 1933, Serial No. 667,526

6 Claims. (Cl. 196—18)

This invention relates to the treatment of hydrocarbon oils, such as petroleum oil residua, or distillates derived from crude petroleum oil, shale oil, or similar sources, and more specifically refers to the treatment of petroleum oil residua, lubricating oil stocks or distillates derived by distillation of crude petroleum oils, preferably under vacuum or partial vacuum, to purify the same by removing unstable hydrocarbons, sulphur bearing hydrocarbons and amorphous or crystalline paraffin wax.

This invention may also be employed in the manufacture of "white oil" stocks to produce liquid petrolatum, or "white oil" stocks which are suitable for use in the manufacture of orchard spray oils, which require the substantial removal of all unsaturated hydrocarbons toxic to foliage.

Our preferred method of treating residua, lubricating oil stocks, or distillates derived from naphthenic base, mixed base, or paraffin base crude oils, consists in dissolving the oil under treatment in liquefied hydrocarbon gases, and while in solution subjecting the mixture to an acid treatment with sulphuric acid at a temperature suitable for the removal of the undesired hydrocarbons and waxes.

The treating temperature may vary through a wide range, depending upon the quality or characteristics of the oil under treatment, a higher temperature being usually used if the oils are derived from a naphthenic base crude petroleum oil, and a lower temperature may be used if the oils are derived from a mixed base or paraffin base crude oil when it is desired to remove amorphous or crystalline wax.

In the removal of waxes from petroleum oils, or those hydrocarbons which cause gelatinization of lubricating oil stocks, the temperature may be varied in our process so as to remove first the waxes congealing at relatively high temperatures, and thereafter further cooling and removing the lower melting or amorphous waxes to the required degree necessary to obtain an oil stock having a desired cold test. By our process a paraffin base oil may be treated so as to yield a lubricating oil having a pour test of 0° F. or lower. To obtain these latter results it is necessary to chill or cool the oil, dissolved in the liquefied hydrocarbon gas, to a temperature considerably below the cold test desired, which in some cases may be as low as -30 to -40° F., to obtain a finished oil having a cold test of zero or lower.

These low temperatures are obtained in our process by a series of cooling operations, in which

the oil to be treated, dissolved in the liquefied hydrocarbon gases, is subjected to heat exchange with the cold outgoing oil mixture in two stages, and may be thereafter further cooled by vaporizing a portion of the liquefied gases contained in the oil under treatment. Also, the liquefied hydrocarbon gases used may be pre-cooled before mixing with the oil by maintaining a reduced pressure on the storage tanks holding the liquefied gases.

The operation of our invention may be also carried out solely for the removal of paraffin wax from oils without acid treatment, in which case the method employed is similar to the method using acid.

In general, our invention comprises treating oil, such as a mineral lubricating oil distillate or residuum, derived from an asphalt base, a mixed base or a paraffin base crude petroleum oil, dissolved in liquefied hydrocarbon gases, with sulphuric acid at temperatures below the freezing temperature of water, settling and removing the major portion of acid reaction products, together with a portion of the paraffin wax content, centrifuging or filtering and removing the remaining portion of the acid reaction products and paraffin wax, and finally separating the liquefied hydrocarbon gas from the treated oil; or the paraffin wax constituents may be removed from the oil without treatment with sulphuric acid.

The liquefied hydrocarbon gases employed serve as a refrigerating agent as well as a solvent for the oil being treated, and may be any of those gases or mixtures thereof which can be extracted from oil well gases, or the gases separated from natural gasoline stocks in stabilizing operations, such as propane, butane, trimethylene, tetramethylene, and isomers thereof which are hydrocarbons having a vapor pressure greater than atmospheric at ordinary atmospheric temperature, and which may also contain small percentages of ethane dissolved therein.

Processes for the treatment of petroleum oil with sulphuric acid or fuming sulphuric acid at low temperatures, employing low boiling temperature liquids as a solvent for the oil and as a refrigerating agent, are known in the art, such as described in our issued United States Patents #1,710,143, #1,710,200, #1,710,201, and #1,810,068, which disclose methods for the treatment of various petroleum oils or distillates thereof at low temperatures, employing liquid sulphur dioxide and liquefied hydrocarbon gases.

Now we have discovered additional improve-

ments thereto which are more specifically adapted for the treatment of lubricating oil stocks containing paraffin wax either in the crystalline or amorphous form, which result in the removal of 5 the wax constituents, together with the simultaneous removal of the acid reaction products if acid has been used in the treatment, by a new system of first settling the acid treated oil dissolved in the solvent, at a temperature sufficiently 10 low to maintain the wax content in a congealed form, by a continuous separating method, thereby removing the larger portion of the acid reaction products, together with a portion of the paraffin wax, then removing the remaining portion of the 15 acid reaction products and wax by filtration or centrifugal action.

An object of the invention is to provide a continuous system for the separation and removal of paraffin wax from mineral oils.

20 Another object of the invention is to provide a continuous method for the production of lubricating oil stock by the extraction of paraffin wax constituents, sulphur bearing hydrocarbons and unstable hydrocarbons from mineral oils.

25 Another object of the invention is to provide a direct cooling system whereby the agent used to reduce the viscosity of the oil under treatment will also serve as a refrigerating agent.

Another object of the invention is to produce 30 transformer oils, lubricating oils, spray oils, mineral medicinal oils and other products of like composition by a continuous sequence of operations, rapidly, economically and without excessive loss of the desired stock.

35 Various other objects and advantages of the present invention will be apparent from the description of the preferred form or example of the process embodying the invention. For this purpose reference is made to the accompanying drawing in which there is illustrated a form of apparatus in which the invention may be performed.

In the drawing, 3 represents generally a tank for holding a supply of the oil to be treated, 45 such as a lubricating oil stock containing paraffin wax. Pipe 1, controlled by valve 2, connects tank 3 to a source of supply, by means of which tank 3 may be maintained at any desired level. From tank 3 the oil is caused to flow through pipe 4 and into the inlet side of pump 6, the rate of flow being governed by operation of valve 5.

50 As the oil passes through pipe 4 it is continuously mixed with and is dissolved in a sufficient amount of liquefied hydrocarbon gases coming 55 from liquefied hydrocarbon gas tank 12 through pipe 13, pump 15, pipe 16 and branch pipe 18, the rate of flow being governed by operation of valves 14, 17, 19 and pump 15. Pipe 18 is connected to pipe 4 near the inlet side of pump 6.

60 The quantity of liquefied hydrocarbon gases which are introduced into the oil stream flowing through pipe 4 depends upon the composition and the viscosity of the oil under treatment; for low viscosity oils as little as one volume of the 65 liquefied gases to five volumes of the oil may be used, and for high viscosity oil as much as five volumes of the liquefied gases to one volume of the oil may be used.

70 Pump 6 discharges the oil, dissolved in the required quantity of liquefied gases, through pipe 7, heat exchanger 8, pipe 9, and then through cooling coil 10. Cooling coil 10 is stationed in tank 11, which is provided with a safety valve 90.

75 As the oil mixture passes through heat exchanger 8 it undergoes a heat exchange with the outgoing

cooled, treated oil mixture, and is thereby cooled to a temperature of approximately 40° F. or lower, and is further cooled in cooling coil 10 to substantially the required treating temperature, which may be 0° F. or lower, depending upon the composition of the oil under treatment and the product desired. For certain oils carrying low paraffin wax content, or when it is desired to extract only the high temperature melting wax from the oil, the treatment may be carried out at any temperature ranging from 0 to 32° F.

5 The cooling of the oil mixture passing through coil 10 is effected by heat exchange with the outgoing treated oil mixture, which may be cooled to any desired temperature, either above or below 15 0° F., by evaporation of a portion of the liquefied gaseous content thereof, produced by maintaining a regulated vacuum on tank 11 through vapor outlet pipe 33, and spraying the treated oil mixture through spray pipe 20 over coil 10. Vapor 20 outlet pipe 33, controlled by valve 41, is connected to the inlet of compressor 36 through pipe 34. Spray pipe 20 is stationed in the upper section of tank 11 and is connected to pipe 21, which conveys the treated oil mixture from centrifuge 22 after final separation of the paraffin wax, or the paraffin wax and acid reaction products.

25 The cooled oil mixture, at the required treating temperature, which may range from 32 to 0° F. or lower, passes from coil 10 through pipe 30 23 and into jet mixer 24. In jet mixer 24 the cooled oil mixture is commingled with the required quantity of sulphuric acid or fuming sulphuric acid necessary to refine the oil to the required degree, such quantities depending upon 35 the percentage of impurities in the oil and the product desired. For lubricating oil stocks the quantity of acid may range from as low as four pounds to as high as seventy pounds per barrel of oil under treatment, and for "white oil" stocks 40 as much as 170 pounds or more may be required. In the treatment of oils requiring large amounts of sulphuric acid, two or more treating operations may be employed.

45 The supply of sulphuric acid or fuming sulphuric acid used in the treating operation is maintained in acid tank 21, and is introduced into jet mixer 24 in a continuous stream flow through pipe 25, controlled by valve 26. Pipe 28, controlled by valve 29, connects acid tank 50 21 to a source of supply of sulphuric acid or fuming sulphuric acid not shown.

55 In order to effect the acid treatment of the oil mixture in jet mixer 24 at a substantially uniform temperature, liquefied hydrocarbon gases, cooled to a temperature below that of the oil mixture, which may be as low as -20° F. or lower, are continuously introduced from tank 32 through pipe 30, controlled by valve 31, into jet mixer 24, along with the acid, in quantities sufficient to extract the heat of the chemical reaction of the acid on the oil. For this purpose a supply 60 of liquefied hydrocarbon gases is maintained in tank 32, cooled to a temperature of approximately -20° F. or lower, by regulation of the vapor pressure in tank 32 through vapor outlet pipe 34, controlled by valve 35, and the operation of compressor 36 which is connected on the inlet side to pipe 34. A pipe controlled by valve 91 is connected to tank 32 at the top for discharging 70 non-condensable gases into the atmosphere.

75 The quantity of liquefied gases employed to extract the heat of the chemical reaction between the oil and acid may range from approximately five to ten per cent by volume or higher, de-

pending upon the quantity of acid employed and the heat evolved by the treatment. In the treatment of certain grades of oil this introduction of cool liquefied gases into the mixer may be eliminated, particularly when small amounts of acid are used, or when the treatment is conducted for the separation of paraffin wax without acid treatment.

From jet mixer 24 the oil mixture and products 10 of reaction pass through pipe 37 and into the inner compartment 39 of an insulated settling tank 38. A vapor pipe 40, controlled by valve 41, connects inner compartment 39 at the top to pipe 42, controlled by valves 43 and 44. Pipe 15 42 connects settling tank 38 through pressure release valve 88 to pipe 34, the vapor inlet to compressor 36, by means of which the oil mixture entering the inner compartment may be further cooled by evaporation of a portion of the liquefied 20 gaseous content of the oil mixture.

The pressure maintained in pipe 42 may be observed through pressure gauge 89.

The vaporized hydrocarbon gases evolved in the cooling and recovery operations, together with the 25 necessary supply of hydrocarbon gases employed for the treating operations, coming from a source not shown through pipe 53, controlled by valve 54, pass into pipe 34. Pipe 34 is connected to the inlet side of compressor 36. Compressor 36 30 compresses the gases to the necessary degree for liquefaction, which may range from approximately 100 to 500 pounds, and discharges the compressed gases through pipe 52, controlled by valve 51, and into condenser coil 55. In condenser coil 55 the heat of compression is extracted by a cooling fluid, such as water, flowing through condenser box 56, and the hydrocarbon gases liquefied.

From condenser coil 55 the liquefied hydrocarbon 40 gases pass through pipe 51, controlled by valve 58, and into tank 12. The necessary quantity of liquefied hydrocarbon gases used for cooling the oil mixture during the acid treatment in jet mixer 24 is conveyed from tank 12 through pipe 16, controlled by valve 17, into tank 32, and cooled as heretofore described.

The acid treated oil mixture and products of reaction pass down through compartment 39 into the bottom section of settling tank 38, and then 50 upward through the outer section of settling tank 38, whereby the major portions of the acid reaction products and paraffin wax content settle to the bottom and collect in the lower section thereof, to which is attached a cylinder piston 55 pump 60. Pump 60 operates so as to discharge the acid reaction products and paraffin wax as they collect in the bottom of the settling tank through pressure regulating valve 61, pipe 62 and into sludge storage tank 63. Storage tank 63 is 60 provided with steam coil 68, by means of which the liquefied hydrocarbon gases retained by the separated reaction products are heated, vaporized and separated. The vaporized gases separated in sludge tank 63 pass therefrom through pipe 46, controlled by valve 45, into pipe 34, and are thereafter compressed, cooled and liquefied for reuse by compressor 36, as heretofore described.

The heat applied to the reaction products in 70 tank 63 liquefies and separates these products into a top layer of liquefied paraffin wax and a bottom layer of acid reaction products or sludge. As the paraffin wax accumulates in tank 63 it overflows through pipe 64 and collects in tank 75 65, and may be thereafter transferred to other

storage through pipe 66, controlled by valve 67. The acid sludge which accumulates in tank 63 may be transferred to a sludge disposal system through pipe 69, controlled by valve 70. Tank 65 is provided with steam heating coil 85 so as to maintain the wax which accumulates therein in a fluid condition.

The acid treated oil mixture, separated from the major portion of the acid reaction products and paraffin wax in settling tank 38, overflows 10 into trough 59 which is stationed in the upper section of tank 38, and passes therefrom through pipe 11 controlled by valve 11' into centrifuge 22, wherein the remaining portion of the acid sludge and paraffin wax are separated from the oil mixture by centrifugal action, the separated products passing out through pipe 73 and into tank 72; or the oil mixture, separated from the major portion of the acid reaction products and paraffin wax or paraffin wax content, may be passed from pipe 11 into pipe a by opening valve a' and closing valve 11'. From pipe a the oil mixture passes 15 through filter b, wherein the remaining portion of the acid sludge and paraffin wax or paraffin wax content is separated by filtration, the separated product passing into tank 72 through pan d and pipe e.

By means of steam coil 77 the separated wax products may be heated and liquefied and then 20 conducted to a storage not shown through pipe 78, controlled by valve 79, and the liquefied gases contained therein vaporized, separated and returned to compressor 36 through pipes 48, 42 and 34, controlled by valves 43 and 44, to be 25 liquefied for reuse.

The treated oil mixture, substantially free from acid reaction products and paraffin wax, passes 30 from centrifuge 22 or filter b through pipe 21 and into tank 11, wherein it is employed as a cooling agent for the incoming oil mixture to be treated, as heretofore described. From tank 11 the treated oil mixture passes through pipe 74, heat exchanger 8, pipe 75, and into the inlet side of pump 76. Pump 76 discharges the treated oil mixture through pipe 82 and into finished oil 35 tank 83, wherein the mixture is heated by means of steam coil 81, and the liquefied gases vaporized and separated from the oil.

The vaporized gases separated from the treated oil in tank 83 pass through pipe 50, controlled 40 by valve 49, pipe 34, and then into the inlet side of compressor 36, where they are compressed, cooled, liquefied and returned to the system for reuse.

The temperature of the liquefied hydrocarbon 45 gases which collect in tank 12 may be lowered to any desired degree by maintaining a regulated reduced pressure in tank 12 through pipe 87, controlled by valve 86, pipe 87 being connected to pipe 34, the inlet to compressor 36.

The finished treated oil which collects in tank 50 83 is transferred to other storage not shown through pipe 84, controlled by valve 80, and may be thereafter subjected to other treatments known in the art, such as neutralization with 55 caustic soda solution and treatment with a de-colorizing agent, to produce a finished oil.

While the process herein described is well adapted for carrying out the objects of the present invention, it is to be understood that various modifications and changes may be made without departing from the spirit of the invention, and the invention includes all such modifications and changes as come within the scope 60 of the appended claims.

We claim:

1. In the process of refining petroleum oil containing paraffin wax, the steps which comprise, mixing the oil with liquefied hydrocarbon gases having a vapor pressure greater than atmospheric at ordinary atmospheric temperature, cooling the mixture to a temperature sufficient to congeal the wax content, treating the cooled mixture with sulphuric acid, passing the cooled acid treated mixture through a settling tank to thereby separate acid reaction products and high melting wax from the oil mixture by settling, passing the oil mixture from the settling tank and separating the remaining portion of the wax from the oil mixture.
2. In the process of refining petroleum oil containing paraffin wax, as in claim 1, in which the remaining portion of the wax content, after settling, is separated from the oil mixture by centrifugal action.
3. In the process of refining petroleum oil containing paraffin wax, as in claim 1 in which the remaining portion of the wax content, after settling, is separated from the oil mixture by filtration.
4. In the process of refining petroleum oil containing crystalline and amorphous wax, the steps which comprise, mixing the oil with liquefied hydrocarbon gases containing propane and butane as principal constituents, cooling the mixture to a temperature sufficient to congeal the wax content, treating the cooled mixture with sulphuric acid, passing the cooled acid treated mixture through a settling tank to thereby separate acid reaction products and crystalline wax from the oil mixture by settling, passing the oil mixture from the settling tank and separating the remaining portion of the wax content. 5
5. In the process of refining petroleum oil containing crystalline and amorphous wax, as in claim 4, in which the remaining portion of the wax content, after settling, is separated from the oil mixture by centrifugal action. 10
6. In the process of refining petroleum oil containing crystalline and amorphous wax, as in claim 4, in which the remaining portion of the wax content, after settling, is separated from the oil mixture by filtration. 15
